CONCRETE BLOCK PACKING MACHINE

Zebe A. Babcock, Cass City, Mich., assignor to
Ben R. Smutek, Detroit, Mich.

Application September 17, 1948, Serial No. 49,702

6 Claims. (Cl. 25—41)

1

My invention relates to concrete block packing machines, of the type wherein the freshly-poured concrete block is subjected to vibration to pack or compact the same.

With the foregoing in view, an object of my invention is to provide an improved concrete block packing machine of the class described.

A further object is to provide an improved concrete block packing machine including means mounting a packing head for linear movement into and out of an operative position engaging a block, means for imparting rapid hammer blows to the head to vibrate the same on said block, a motor operating said vibrating means, and means automatically starting and stopping said motor upon movement of said head into and out of said operative position.

Other objects and advantages reside in the particular structure of the invention, the structure of the elements forming the several parts thereof, combination and arrangement of said elements together with sub-combinations thereof, all of which will be readily apparent to those skilled in the art upon reference to the attached drawings in connection with the following specification, wherein the invention is shown, described and claimed.

In the drawings:

Figure 1 is an elevational view showing the device according to the invention, parts being broken away;

Figure 2 is a vertical sectional view through the device of Figure 1;

Figure 3 is an end view of the device looking from the left of Figure 1;

Figure 4 is a vertical sectional view taken at right angles to the section of Figure 2;

Figure 5 is a horizontal sectional view taken substantially on the plane of the line 5—5 of Figure 4.

Referring specifically to the drawings, wherein like reference characters have been used throughout the several views to designate like parts, 10 designates a pedestal of tubular configuration mounted on any suitable base, not shown. The pedestal 10 has pivotally mounted therein a vertical stem 11. An upper portion of the pedestal 10 has fixed thereto a collar 12 which may be secured in adjusted relation thereon by a thumb screw 14. The collar 12 has fixed thereon an up-standing arm 13 comprising a limit stop for an arm 15 fixed to the upper end of the stem 11. The arm 15 extends laterally of the pedestal 10 and the free outer end thereof is formed with a vertically-extending sleeve 16, the purpose of

which will be apparent later. It is apparent from the foregoing that the sleeve 16 is swingable with the arm 15 into and out of a position overlying any suitable support or table 17 for a mold block 18 for a concrete block 19. Thus, the limit stop 13 may be so adjusted as to stop the arm 15 and sleeve 16 when the same are so positioned that the sleeve 16 overlies the block 19 axially thereof.

10 The sleeve 16 has fixed thereon adjacent the upper edge thereof a pair of laterally-spaced horizontal journals 23 in which is journaled a shaft 24. The shaft 24 has fixed thereon between the journals 23 a pinion 25. One end of the shaft 24 extends laterally outwardly of the sleeve 16 and is formed with a crank 26, whereby to rotate the shaft and pinion. The housing 20 has a vertically-disposed rack 27 formed on one side thereof in operative mesh with the pinion 25, whereby rotation of the shaft 24 causes vertical adjusting movement of the housing 20 in the sleeve 16. The sleeve 16 may be vertically slotted, as at 37, to accommodate the vertical movement of the rack 27. The lower end of the housing 20 extends below the sleeve 16 and has fixed thereto by any suitable means 21 a packing head 22 which preferably substantially conforms to the interior dimensions of the mold box 18, whereby upon downward movement of the sleeve 20, the head 22 is brought into operative engagement with the mold block 19.

To lock the housing 20 in a vertically-adjusted position relative to the sleeve 16, there is provided a bracket 28 including a spring housing 30 through which the stem 29 of latch extends. The latch includes a laterally-directed arm 39 extending behind the sleeve 16 and inwardly-directed latch dog 31 which is substantially parallel to the stem 29. The latch dog 31 is slidable in a tubular boss 32 formed on the side of the sleeve 16 toward the housing 20. The housing 20 is provided with a vertical series of latch detents 33 with which the latch dog 31 is adapted to be selectively engaged to lock the housing in vertically-adjusted positions relative to the sleeve. The bracket 28, as aforesaid, is hollow and provides an enclosure for a coil spring 35 concentrically disposed about the stem 29. The stem 29 is preferably formed with a collar or cross-pin 36 40 interiorly of the housing and operatively engaging the spring 35 to compress the same when the stem 29 is moved from right to left, Figure 5. A finger grip 34 may be formed on the free end of the stem 29. Thus, when the stem 29 is pushed 50 from right to left, Figure 5, the dog 31 is disen-

gaged from the latch detent 33 to permit vertical adjustment of the housing 20 relative to the sleeve 16 by means of the rack and pinion arrangement previously described.

A substantially cylindrical hammer 40 is vertically reciprocable inwardly of the sleeve 20 to impart vibratory hammer blows to the head 22, whereby the vibration thereby created is transmitted to the concrete block 19 to compact the same in a well known manner. The upper end of the hammer 40 is uniformly reduced to provide a substantially annular shoulder 41 defining an axially upwardly-directed stem 42 for the hammer. The stem 42 extends through a hole 43 in a bracket 44 rigidly secured in any suitable manner to the upper end of the housing 20 transversely thereof. A coil spring 45 is concentrically disposed about the stem 42 inwardly of the housing 20 and the lower end thereof bears against the shoulder 41, while the upper end of such spring bears against the under surface of the bracket 44. Thus, the spring 45 loads the hammer for downward movement into engagement with the head 22.

To reciprocate the hammer 40, the upper end of the stem 42 thereof is slotted, as at 46, for the reception of one arm 47 of a rock lever 48. The rock lever 48 is fixed on a cross-shaft 49 which is journaled for rocking movement in a pair of vertically-directed journal-providing ears 50 carried by the bracket 44 on the upper surface thereof. The other arm 51 of the rock lever 48 extends in the opposite direction below a shaft 52 which is likewise journaled for rotation between the ears 50. The shaft 52 has fixed thereon for rotation therewith a cam 53 which may be provided with a pair of diametrically oppositely-disposed cam lobes 54 adapted to engage the arm 51 of the rock lever 48 and rock the same. Such rocking movement through the opposite arm 47 reciprocates the hammer 40, such reciprocation being accelerated in a downward direction by the thrust of the spring 45 in a well known manner. One end of the shaft 52 extends laterally outwardly of the ears 50 and has fixed thereon any suitable pulley 55 which is connected by means of a belt 56 to the drive pulley 57 of an electric motor 58. The motor 58 is controlled automatically by means of an automatic switch carried by switch housing 59 fixed to the upper end of the sleeve 16 in any suitable manner. The housing 59 includes a switch button 60 which extends laterally outwardly of the housing and is biased in an outward position by any suitable means, not shown, whereby to maintain the switch, not shown, in the housing 59 in an open position. Any suitable cable 63 connects the switch housing with a second switch housing 65 carried by the motor which contains the lead 64 to any suitable source of electric current. The bracket 44 includes a rigid depending arm 62 which extends downwardly toward the switch button 60. The switch button 60 is provided with a cam surface 61 in the path of the lower end of the arm 62 as the housing 20 and platform 44 is moved downwardly toward the operative position for the head 22. Thus, as the lower end of the arm 62 engages the switch button 60, the button is moved laterally from left to right, Figures 1 and 2, to close the switch and thereby close a circuit to the motor 58. In this connection, it is assumed that the switch for the housing 65 on the motor is already in the closed position. Thus, as an operator of the machine cranks the housing 20 downwardly to bring the head 22 to an

operative position in engagement with a block 19, the motor 58 is automatically started by the engagement of the arm 63 with the switch button 60. Thus, by the time the head 22 is engaged with the block 19, the hammer 40 is reciprocating in the housing 20 and imparting vibration to the head 22. After the head is engaged with the block 19, such vibration continues until the block 19 is compacted or packed to a desired firmness. Meanwhile, the parts may be locked in this operative position by means of the latch dog 31 aforesaid. When the block 19 has been sufficiently compacted, the latch dog 31 is released and the housing 20 cranked upwardly until the arm 62 clears the switch button 60, at which time the motor 58 is automatically stopped by virtue of the opening of the circuit thereto. Thus, the mold box 18 and the block 19 contained therein may be removed from the table 17 and a new uncompacted block substituted therefor. Meanwhile, the sleeve 16 has been swung laterally out of registry with the table 17. When a new mold box 18 has been placed on the table 17, the arm 15 is swung back into engagement with the stop 13, whereby the parts are automatically centered over the mold box 18. Thereafter, the housing 20 is cranked downwardly to bring the head 22 into operative position relative to the block 19. This cycle is repeated indefinitely until the end of a working period, at which time the motor may be permanently shut off by the switch in the switch housing 65.

While I have shown and described what is now thought to be a preferred embodiment of my invention, it is to be understood that the same is susceptible of other forms and expressions. Consequently, I do not limit myself to the precise structure shown and described hereinabove except as hereinafter claimed.

40 I claim:

1. A concrete block packing machine, comprising a pedestal, an arm pivotally adjustable on said pedestal, a vertically-disposed sleeve formed on said arm, a tubular housing vertically slidable in said sleeve, said housing including a lower end providing a packing head, a shaft including a crank journaled on said sleeve, a pinion fixed to said shaft, a rack fixed to said housing and operatively meshed with said pinion whereby to adjust said housing vertically in said sleeve and move said head into and out of an operative position, a hammer vertically reciprocable in said housing for imparting packing blows to said head, said housing including an upper end providing a bracket, a motor mounted on said bracket, and means operatively connecting said motor to said hammer for reciprocating the latter.

2. A concrete block packing machine, comprising a pedestal, an arm pivotally adjustable on said pedestal, a vertically-disposed sleeve formed on said arm, a tubular housing vertically slidable in said sleeve, said housing including a lower end providing a packing head, a shaft including a crank journaled on said sleeve, a pinion fixed to said shaft, a rack fixed to said housing and operatively meshed with said pinion whereby to adjust said housing vertically in said sleeve and move said head into and out of an operative position, a latch carried by said sleeve, said housing being formed with a vertically-disposed series of latch detents engageable with said latch for releasably locking said housing in a selected vertically-adjusted position relative to said sleeve, a hammer vertically reciprocable in said housing 75 for imparting packing blows to said head, said

housing including an upper end providing a bracket, a motor mounted on said bracket, and means operatively connecting said motor to said hammer for reciprocating the latter.

3. A concrete block packing machine, comprising a base, a vertically-disposed sleeve formed on said base, a tubular housing vertically slidable in said sleeve, said housing including a lower end providing a packing head, a shaft including a crank journaled on said sleeve transversely thereof, a pinion fixed to said shaft, a rack fixed to said housing longitudinally thereof and operatively meshed with said pinion whereby to adjust said housing vertically in said sleeve and move said head into and out of an operative position, a latch carried by said sleeve, said housing being formed with a vertically-disposed series of latch detents engageable with said latch for releasably locking said housing in a selected vertically-adjusted position relative to said sleeve, said housing including an upper end providing a bracket, an electric motor carried by said bracket, a switch for said motor carried by said sleeve, means biasing said switch to an open position, an arm fixed to said bracket and depending therefrom, and said arm being engageable with said switch to close the same upon downward movement of said bracket and housing to move said head to said operative position.

4. A concrete block packing machine comprising a pedestal, an arm pivotally adjustable on said pedestal, a vertically disposed sleeve formed on said arm, a tubular housing vertically slidable in said sleeve, a packing head secured to the lower end of said housing, means operatively interconnecting said sleeve and housing for adjusting the latter vertically in said sleeve to thereby move said head into and out of an operative position, means carried by said sleeve and engageable with said housing for releasably locking said housing in a selected vertically adjusted position relative to said sleeve, a hammer vertically reciprocable in said housing for imparting packing blows to said head, said housing including an upper end providing a bracket, a motor mounted on said bracket, and means operatively connecting said motor to said hammer for reciprocating the latter.

5. A concrete block packing machine comprising a pedestal, an arm pivotally adjustable on

said pedestal, a vertically disposed sleeve formed on said arm, a tubular housing vertically slideable in said sleeve, a packing head secured to the lower end of said housing, a shaft including a crank journaled on said sleeve, a pinion fixed to said shaft, a rack fixed to said housing and operatively meshed with said pinion whereby to adjust said housing vertically in said sleeve and move said head into and out of an operative position, means carried by said sleeve and engageable with said housing for releasably locking said housing in a selected vertically adjusted position relative to said sleeve, a hammer vertically reciprocable in said housing for imparting packing blows to said head, said housing including an upper end providing a bracket, a motor mounted on said bracket, and means operatively connecting said motor to said hammer for reciprocating the latter.

6. A concrete block packing machine comprising a pedestal, an arm pivotally adjustable on said pedestal, a vertically disposed sleeve formed on said arm, a tubular housing vertically slideable in said sleeve, a packing head secured to the lower end of said housing, means operatively interconnecting said sleeve and housing for adjusting the latter vertically in said sleeve to thereby move said head into and out of an operative position, a latch carried by said sleeve, said housing being provided with a vertically disposed series of latch detents engageable with said latch, for releasably locking said housing in a selected vertically adjusted position relative to said sleeve, a hammer vertically reciprocable in said housing for imparting packing blows to said head, said housing including an upper end providing a bracket, a motor mounted on said bracket, and means operatively connecting said motor to said hammer for reciprocating the latter.
